UNITED STATES PATENT OFFICE.

PHILIP H. LONG, OF NEWARK, NEW JERSEY.

DESIGN FOR A HANDLE FOR BUTTON-HOOKS, &c.

SPECIFICATION forming part of Design No. 27,501, dated August 10, 1897.

Application filed July 3, 1897. Serial No. 643,466. Term of patent 7 years.

To all whom it may concern:

Be it known that I, PHILIP H. LONG, a citizen of Great Britain, residing at Newark, in the county of Essex and State of New Jersey, have invented and produced a new and original Design for Handles for Button-Hooks, Manicure Articles, &c.; and I do hereby declare the following to be a full, clear, and exact description of the invention, such as will 5 enable others skilled in the art to which it appertains to make and use the same, reference being had to the accompanying drawing, and to letters of reference marked thereon, which forms a part of this specification.

10 15 The single figure of the drawing is deemed sufficient to illustrate the character of the design.

As shown in the drawing, the leading or material feature of my design consists of the 20 handle irregularly scalloped at the opposite edges and on the side face having the flower-shaped ornamentation at the center, the scroll ornamentation at the opposite ends, and the shield bordered by conventional leaves, which 25 latter are continued around said flower-shaped ornament.

In said drawing, *a* indicates the handle. *b*, *c*, *d*, *e*, and *f* are series of scallops uniformly 30 ornamenting the opposite edges of the handle, the convex scallops *b* nearest the button-hook at the narrower part of the handle and the convex curves of the scallops *c* having concavous curves *g* between and the said 35 curves lying in diverging lines flaring toward the upper end of the handle, where the handle is ornamented at its terminal edges by

oppositely-divergent series of small scallops *h h h*, giving something like a shell effect of ornamentation.

Between the oppositely-convex curves *b b* 40 the handle is ornamented by conventional scroll or feather shaped ornaments *i*. At the opposite end of the handle, between the series of small scallops *h h h* and *h h h*, the handle is ornamented by similar scrolls or feather- 45 shaped decorations *j j j*.

Between the oppositely-convex curves or scallops *f f* the shield or open ground *k* is bordered by conventional leaf-decorations *l l*, which are dentate on their inner edges and 50 curved in lines approximately parallel with the curves *f f* on their outer sides.

At about the center of the handle, between the scallops *d d*, is a flower-shaped ornament *m*, which is more or less fully inclosed by 55 conventional leaves *o p*, which are extensions of the curved lines of leaves *l l* and the dentations of which are on the outer sides of the ornaments also. Between the scallops *c c* is a conventional scroll *q*. 60

What I claim is—

The design for a handle for button-hooks, manicure articles, &c., substantially as shown and described.

In testimony that I claim the foregoing I 65 have hereunto set my hand this 2d day of July, 1897.

PHILIP H. LONG.
